UNITED STATES PATENT OFFICE.

THOS. L. BRAYNARD, OF NEW YORK, N. Y.

REIN-HOLDER.

Specification of Letters Patent No. 31,698, dated March 19, 1861.

To all whom it may concern:

Be it known that I, THOMAS L. BRAYNARD, residing in New York, in the county of New York, in the State of New York, have invented a new Article for the Holding of the Reins or Securing Them in a Proper Position to the Vehicle when the Vehicle is Left by the Driver; and I do hereby declare that the following is a full and exact 10 description thereof, reference being had to the annexed drawings and working model which accompany this application.

The following is a description of the rein holder, *viz.*:

15 Two eccentrics marked in Figure 1 as "A" and "B" run on two upright shafts marked "a" and "b" the edges of which where they come in contact being grooved, said eccentrics "A" and "B" resting upon 20 a platform "D" and the bottom of each eccentric hollowed out as shown in Fig. "4" and in which is a spiral or coil spring marked *f* one end of which is fastened to the eccentric at "d" and the other end to 25 the upright shaft marked "c" in Fig. "4," upon which the eccentric runs. The platform upon which the eccentrics rest, has a screw running through it, by which the rein holder is fastened to the vehicle. The cuts 30 in Fig. 1 show the head of the screw which screws into the shafts "c" and fastens the eccentric to the shaft, so that the drawing out of the reins shall not draw the eccentric off of the shaft. The letters "C C" are the 35 reins which are now drawn between the eccentrics "A B" and are now held by the nip-

ping of the eccentrics, and the strain upon the reins by the jerking of the horse's head only tightens the hold of the eccentrics upon them.

"E" in Fig. 1 is the post of the carman's truck upon which the rein holder is secured.

Fig. 2 shows the eccentrics open as the reins pass through them, and Fig. 3 the closing of them upon the reins.

The driver in leaving his vehicle, only has to draw the reins through the eccentrics and at once has them in a secure position, and no danger of their getting under the horse's feet.

The letters "e e" in Fig. 2 show two pins which keep the eccentrics from acting farther than that point, said pins being fastened into the platform "D."

I am aware that devices have been contrived to hold straps, &c., by the use of cam levers acting against a fixed point or shoulder, and therefore do not claim generally the use of cams to hold reins, &c.; but

What I claim as my invention and desire to secure by Letters Patent is—

The arrangement and combination of the two eccentrics A and B, substantially as described, for the purpose of holding or fastening reins, straps, &c., by the action and revolution of such eccentrics toward each other.

THOS. L. BRAYNARD.
